Int. Cl. D15—08

U.S. Cl. D92—15

FIG. 1 is a side perspective view of a thread canister showing my new design with one elongated vertical rib of a set of three symmetrical vertical ribs shown disposed near the lower end;

FIG. 2 shows an elevational side view of the thread canister of FIG. 1 rotated 120° from the view of FIG. 1; and

FIG. 3 illustrates a top view of the thread canister, with the three ribs shown equally spaced about the thread canister.

I claim:

The ornamental design for a thread canister, as shown and described.
